United States Patent Office

Des. 204,187
Patented Mar. 29, 1966

204,187

DOOR CLOSER

Donald A. Schulz, Wauwatosa, Wis., assignor to S-B
Manufacturing Company, Milwaukee, Wis., a corpora-
tion of Wisconsin

Filed Aug. 17, 1965, Ser. No. 86,661

Term of patent 14 years

(Cl. D10—7)

FIG. 4

FIG. 7

FIG. 6

FIG. 5

FIG. 1 is a top plan view of my new design door closer.
 FIG. 2 is a side elevational view thereof.

FIG. 3 is a bottom plan view thereof.

FIG. 4 is a side elevational view thereof.

FIG. 5 is an end elevational view thereof taken from the end carrying the frame mounting bracket.

FIG. 6 is an end elevational view thereof taken from the end carrying the door mounting bracket.

FIG. 7 is a cross sectional view taken on line 7-7 of FIG. 4 and showing only the profile thereof.

I claim:

The ornamental design for a door closer, as shown.
